Inventor:
John Ellis.

UNITED STATES PATENT OFFICE.

JOHN ELLIS, OF DETROIT, MICHIGAN.

GATE-LATCH.

Specification of Letters Patent No. 32,990, dated August 6, 1861.

To all whom it may concern:

Be it known that I, JOHN ELLIS, of Detroit, in the county of Wayne and State of Michigan, have invented certain new and useful Improvements in Gate-Latches; and I do hereby declare that the following is a full and complete description of the construction and operation of the same, reference being had to the accompanying drawings, making a part of this specification, in which—

Figure 1, is a perspective view of the catch entire. Fig. 2, is a side view. Figs. 3, and 4, are front views of the case, with the cap removed. Fig. 5, is a perspective view of the case, and cap, detached from each other. Fig. 6, is a view of the latch.

The same letters refer to like parts, in the different figures.

20 My improvement relates, to a catch and latch, so constructed, that the gate can be opened and closed either way, and will fasten itself, at once, and not pass through, and swing back and forth.

25 In the figures A, represents, the back part of the case, that is designed to be secured to the post, by screws passing through the holes a, seen in Figs. 3, 4 and 5.

30 B, and B, are projections, forming a part of the case, and that support the tumbler C, as shown in Figs. 3, 4, and 5, and D, represents the catch, with curved lips or planes D', connected to the lower end of the case, and forming a part of it.

35 When the gate is shut or open, the tumbler C, resting on the pieces B, B, is vertical, in the position indicated by the dotted lines in Fig. 3, and if the gate is latched, as

indicated, by raising the latch H, the tumbler C, is elevated, and the gate can be 40 opened as well one way as the other, for the curved planes D', are alike, and the tumbler C, being in the center, the latch H, can pass out either way alike. But if the gate is 45 open and swings shut, the latch H, slides up over the curved plane D', coming in contact with the tumbler, and forcing it along, until H, falls into the catch D, when the tumbler returns to its former place.

The gate cannot swing through, when 50 shutting either way, however great its momentum, for the pieces B, B, prevent the tumbler, from swinging out of the way, any further than shown, and indicated by the dotted lines C', in Fig. 4, in which, it will 55 readily be seen, that the space is not near wide enough for the latch to pass through, and it will of course fall down into the catch D.

F, represents the cap or cover, that is 60 placed over the upper part of the case and tumbler. It is represented detached in Fig. 5, and is secured to the post by screws, passing through the holes b, b, when in use.

Fig. 6, is a perspective view of the latch 65 H, that is connected to the gate.

What I claim as my improvement and desire to secure by Letters Patent is:

The tumbler C, in combination with the latch and catch, when operating conjointly, 70 substantially, as set forth, for the purpose described.

JOHN ELLIS.
